(57) **CLAIM**

The ornamental design for a pizza slice container, as shown and described.

DESCRIPTION

FIG. 1 is a right-side view of a pizza slice container, the left-side view being a mirror image thereof;

FIG. 2 is a top view thereof, the bottom view being a mirror image thereof;

FIG. 3 is a front view thereof;

FIG. 4 is a rear view thereof;

FIG. 5 is a front isometric view thereof; the rear end being elevated at an angle;

FIG. 6 is a front isometric view of the pizza slice container;
FIG. 7 is the front isometric view thereof, with one of the front flaps and one of the rear flaps cooperatively bended to cover the front and rear openings.

FIG. 8 is the front isometric view shown in FIG. 7, with both front flaps and both rear flaps cooperatively bended to completely close the front and rear openings.

FIG. 9 is a right-side view thereof, with both front flaps and both rear flaps cooperatively bended to completely close the front and rear openings; and,

FIG. 10 is a top view thereof, with both front flaps and both rear flaps cooperatively bended to completely close the front and rear openings.

The broken lines represent environmental structure and form no part of the claimed design.
